Products Co., Chicago, Ill., a corporation of
Illinois

Application April 23, 1941, Serial No. 389,946

9 Claims. (Cl. 273—118)

This invention relates to ball rolling game apparatus including a table top inclined slightly to horizontal, and over which balls are rollable. Games of this general class have heretofore been provided with suitable target devices and/or switch devices mounted on the table top in position to be encountered by a ball. Certain of said devices, as heretofore employed, are connected in electrical circuits which are adapted to be closed or opened, when said devices are encountered by a ball for operating other devices or apparatus. Such devices are usually employed for the purpose of providing a game which will create and/or maintain interest and which possesses player appeal.

The present invention is directed to a novel combination target and switch device which provides novel control of a number of separate electrical circuits for actuating a wide variety of auxiliary devices and apparatus.

One of the objects of this invention is to provide a novel form of combined target and switch device mounted on the table top in position to be encountered and actuated by a ball rolling thereby for making and breaking one or a plurality of electrical circuits.

Another object is to provide a novel and improved target and switch device in the form of a rotatable turnstile having a plurality of arms adapted to be positioned to be encountered and moved by a ball traveling over the table top, together with a switch structure adapted to be actuated in response to movement of the turnstile for controlling a plurality of separate electrical circuits.

A further object is to provide a novel and improved combination target and switch device for controlling the make and break of a plurality of electrical circuits for operating various apparatus, and wherein said improved device obviates the use of complicated and expensive electromagnetic devices and mechanisms, such as heretofore employed.

Still another object is to provide a novel combination target and switch device which lends itself for use in a multiplicity of novel arrangements for operating electrical circuits controlling various electrical apparatus or devices such as scoring devices, recording apparatus, etc., as well as novel lighting arrangements of the game.

Other objects and advantages of this invention will be apparent from the following description, taken in connection with the accompanying drawings in which:

Figure 1 is a fragmentary plan view of the table top of a ball rolling game apparatus upon which is mounted the combination target and switch device embodying the present invention.

5 Figure 2 is an enlarged vertical sectional view through the combined target and switch device, taken substantially as indicated at line 2—2 on Figure 1.

Figure 3 is a horizontal sectional view through 10 the target device taken as indicated at line 3—3 on Figure 2.

Figure 4 is a horizontal sectional view through a portion of the switch device taken as indicated at line 4—4 on Figure 2; and

15 Figure 5 is a diagrammatic illustration of an electrical circuit including our novel combination target and switch device.

The combination target and switch device embodying the present invention includes a target 20 structure 10 of generally triangular form as seen in the drawings. Said target structure is composed of a body 11 and a removable cap or head piece 12, said body and head piece preferably being formed of plastic material for purpose of color effect. The cap 12 is preferably translucent to emit light from an electric lamp 14 mounted within the body 11, and carried in a socket structure indicated generally at 15, secured to the underside of a table top designated at 16. 25 The target 11 is fixedly secured to the table top 16 in any suitable manner and in the present construction, as will hereinafter be described, is fixedly secured by common fastening means associated with a switch device mounted below the 30 table top 16, as hereinafter described.

35 Mounted within the body 11 of the target device is a turnstile 18 disposed in a horizontal plane in substantially parallel spaced apart relation to the top surface of the table top 16. Said turnstile includes a multiplicity of laterally extending radial arms 19 which are adapted to be sequentially rotated through a slot 20 formed in the side wall 21 of the body 11. Said side wall 21 is of substantial length and is substantially upright and straight, in effect serves as a guide wall for a ball rolling over the table top.

40 Any suitable means may be provided for cooperation with the guide wall 21 of the target device, disposed in spaced apart relation thereto, so as to form a relatively narrow passageway 23 through which a ball traveling over the table top may roll. As herein shown, the cooperating guide surface is a surface corresponding to the 45 surface 21 of a target body structure 25 of gen-

erally the same triangular formation as the body 11 and cap 12. It is to be understood that the use of the target structure 25 in conjunction with the target structure 10, containing the turnstile, is primarily for the purpose of appearance and it will be apparent that any suitable means may be employed to provide a relatively straight guide surface disposed in substantially parallel spaced apart relation to the guide wall 21 to form a relatively narrow passageway through which a ball may travel. The target device 25 is rigidly secured in position on the table top 16 by a pair of screws 26 extending through the table top 16 and engaging in bosses 27 formed in the interior of the body of the target device 25, as seen in Figure 2 of the drawings.

The target device 10, which as above mentioned is of generally triangular outline, has its two adjoining walls, other than the wall 21, surrounded by an annulus or band 28 of resilient material, preferably of rubber. Since it is important that the guide wall 21 be free and unobstructed so as not to retard the speed of the ball rolling through the passageway 23, said band of material at the ends of said walls, adjacent the ends of the wall 21, is seated in notches 11a formed in the upper edge of the body 11 so as to permit disposition of the intermediate portion of the band 28 within said body 11 as seen in the drawings. The purpose of the resilient band 28 surrounding the two adjacent outer walls of the target 10, is to provide a suitable resilient contact surface adapted to be engaged by a ball traveling over the table top 16 for causing rebound of the ball over the top 16. The annular band 28, in addition to economy, and due to the notches 11a, facilitates the mounting and assembly of the band on the body 11 of the target device. To insure proper anchorage of the band 28 in position on the outer walls of the body, said outer walls are preferably formed with a recess as indicated at 11b to form a seat for the band, which is of circular cross section. Inasmuch as the target device 25 is of generally similar construction to the target device 10, a resilient band 28 is employed in a similar fashion.

As may be seen in Figure 2 of the drawings, the arms 19 of the turnstile are adapted to be projected into the passageway 23 in position to be encountered and moved by a ball traveling through said passageway, over the table top. The shape of the arms of the turnstile is considered important, and as herein shown, the edges defining the arms are so shaped that the outer end of the arm when encountered by a ball remains in contact with the ball during the entire period of engagement and movement thereof by said ball as it passes through said passageway 23. Such shape of the arms insures that the force of the ball is applied to the outermost end portion of the arm so as to obtain the maximum leverage action of the ball against said arm. It will also be noted that the arms of said turnstile are so dimensioned that when encountered by a ball passing through the passageway 23, the turnstile is rotated by the engaged arm and said arm arrives at a position where it is disengaged by the ball substantially as seen in Figure 3 of the drawings, so as to dispose the next succeeding arm in proper position in the passageway 23 for encounter by the next ball traveling through said passageway.

The turnstile as seen in Figure 2 of the drawings is rigidly attached to a vertically disposed shaft 30 and said turnstile is supported in proper

position by sleeves 31 and 32 surrounding the shaft with the sleeve 32 seated in a switch device indicated generally at 35, fixedly connected to the underside of the table top 16 and to the target device 10.

The switch device includes a fixed panel 37 of insulating material secured by screws 38 to the table top 16 and to the body 11 of the target device 10 by threading in bosses, not shown, but which may be understood to be similar to bosses 27 of the target device 25. Mounted on the underside of the stationary member 37 are two spaced apart concentric conductor rings 40 and 41, and surrounding said outermost ring 41 are two concentric, circumferentially spaced apart series of electrical contacts 42 and 43 respectively. Fixedly secured on the lower end of the shaft 30 is a rotatable member 45, secured by a collar 46 on the lower end of said shaft. Projecting upwardly from said rotatable member 45 are two sets of spring pressed contact fingers 48, 49 and 50, 51, respectively. As may be seen in Figure 2 of the drawings, contact finger 48 is disposed in position for engaging the outer series of fixed contacts 43 on the stationary member 37. The spring contact 49 is in engagement with the conductor ring 41, and spring contact 50 is in engagement with the conductor ring 40, while the spring contact 51 is in position to engage the contacts of the inner series of contacts 42. The respective contacts 43 and 49 are connected at their free ends by a conductor wire 53, while the contacts 50 and 51 are connected together by a conductor wire 54 so as to complete portions of electrical circuits from the respective conductor rings to a respective contact that may be in registration with the respective spring contact fingers 48 and 51. The position of the two separate sets of spring contacts and conductor rings is such as to permit energizing different sets of electrical circuits employing different voltages or amperages, which may be desirable for operating different types of electrical apparatus.

It will now be apparent that in view of the form of turnstile herein shown having four equally spaced apart arms 19, that each time the turnstile is operated by a ball traveling through the passageway 23, the respective sets of spring contacts are likewise moved a quarter revolution with respect to the stationary or fixed panel 37. It may be understood that after completion of each quarter revolution of the turnstile, the arrangement may be such that the spring contacts may complete portions of different electrical circuits and which circuit portions will remain intact unless interrupted by some timing apparatus or other control apparatus, until the turnstile is again actuated by a ball. It will be noted from Figure 4 of the drawings that we provide intermediate contacts, which may for convenience be designated 42a and 43a, adapted to be temporarily engaged by the respective spring pressed contacts 43 and 51, said spring contacts are moved from one arrested position to the next arrested position, corresponding to the positions of the turnstile after actuation by a ball. These intermediate contacts may be a part of auxiliary electrical circuits which are adapted to be temporarily completed during the transitory movement of the yielding contact fingers in their movement from one arrested position to the next arrested position.

Referring now to Figure 5 of the drawings, we have shown an illustrative wiring diagram in

connection with the switch device 35 wherein the series of intermediate contacts 42a and more particularly the contacts upon which the yielding contact finger 51 becomes arrested after movement of the turnstile, are shown connected by conductor wires 60, 61, 62 and 63 to electric lamps designated as 64, 65, 66 and 67. As illustrated, said lamps may be housed within conventional bumper devices, such as indicated generally at A, in Figure 1 of the drawings. The other terminal of each of the other respective lamps is connected to a main conductor wire 68, which in turn is connected to one terminal of a source of energy indicated at 69. The other terminal of said source of energy is connected by a conductor wire 70 to the innermost conductor ring 40. It will now be apparent that as the turnstile rotates a quarter revolution during each actuation by a ball, the respective contacts 42a to which the conductor wires 60, 61, 62 and 63 are connected, are temporarily made and thereby temporarily energize a corresponding light of the lights indicated at 64, 65, 66 and 67. If desired, the conductor wires 60, 61, 62 and 63 may be connected to the other contacts 42 of said inner series so that one of said lights 64, 65, 66 and 67, will always remain energized when the turnstile is arrested, and the intermediate contacts 42a may be connected in auxiliary electrical circuits for temporary completion during the transitory movement of the turnstile from one arrested position of adjustment to the other arrested position of adjustment.

A switch indicated at 72 is provided in the conductor wire 68 and which may be understood to correspond to a suitable switch operated by coin operated mechanism of the game apparatus. As well known, there is usually associated with such type of switches, suitable timing mechanism for effecting opening of the main electrical circuit after a predetermined interval of time. We have also shown in this wiring diagram a circuit for the light 14 which is disposed within the target 10, and said light 14 is connected by a conductor wire 74 to the conductor wire 70 and by conductor wire 75 to the conductor wire 68 beyond the switch 72, so as to remain energized while switch 72 is closed.

It will be apparent that our novel combination target and switch device readily lends itself for use in a relatively wide variety of electrical circuits for controlling various types of devices and apparatus used in connection with ball rolling game apparatus. Such a device has a special advantage in that it permits adaption to electrical circuits as now employed and permits dispensing with complicated and relatively expensive electromagnetic operated devices and mechanisms which serve to control other circuits and apparatus.

Although we have herein shown and described a preferred embodiment of our invention, manifestly it is capable of modification and rearrangement without departing from the spirit and scope thereof. We do not, therefore, wish to be understood as limiting this invention to the precise embodiment herein disclosed, except as we may be so limited by the appended claims.

We claim as our invention:

1. A target for use with a ball rolling game having a table top tilted slightly to horizontal and over which balls are rollable, said target comprising a member adapted to be mounted on the table top and providing a ball guiding surface, a turnstile adapted to be mounted on said

5 table top adjacent said guide surface for rotation in a plane in substantially parallel spaced apart relation to the surface of said table top, said turnstile including a plurality of laterally extending arms, disposed in correlation to said guide surface to present said arms sequentially in overlapping relation to said guide surface in position to be engaged by a ball rolling over said table top, for rotating said turnstile, and means actuated in response to such rotative movement of the turnstile, for operating other apparatus associated with the ball rolling game.

2. A target for use with a ball rolling game having a table top tilted slightly to horizontal and over which balls are rollable, said target comprising means adapted to be mounted on the table top and providing a pair of cooperating spaced apart guide surfaces to form a relatively narrow passageway for a ball rolling over said table top, a turnstile adapted to be mounted on said table top for rotating about an upright axis, in a plane spaced above the surface of said table top, said turnstile having a plurality of circumferentially spaced apart laterally extending arms, said turnstile being so correlated to one of said guide surfaces that one of said arms normally extends into said passageway in position to be engaged and rotated by a ball traveling through said passageway, and means connected to and actuated by such rotative movement of the turnstile, for operating other apparatus associated with the ball rolling game.

3. A target for use with a ball rolling game having a table top tilted slightly to horizontal and over which balls are rollable, said target comprising means adapted to be mounted on the table top and providing a pair of cooperating spaced apart guide surfaces to form a relatively narrow passageway for a ball rolling over said table top, a turnstile adapted to be mounted on said table top for rotating about an upright axis, in a plane spaced above the surface of said table top, said turnstile having a plurality of circumferentially spaced apart laterally extending arms, said turnstile being so correlated to one of said guide surfaces that one of said arms normally extends into said passageway in position to be engaged and rotated by a ball traveling through said passageway, the ball engaging 45 surface of each arm of the turnstile being so formed that the ball engages the outer end of the arm during the entire time said ball remains in contact with said arm, and means connected to and actuated by such rotative movement of the turnstile, for operating other apparatus associated with the ball rolling game.

4. A target for use with a ball rolling game having a table top tilted slightly to horizontal and over which balls are rollable, said target comprising means adapted to be mounted on the table top and providing a pair of cooperating spaced apart guide surfaces to form a relatively narrow passageway for a ball rolling over said table top, a turnstile adapted to be mounted on 50 said table top for rotating about an upright axis, in a plane spaced above the surface of said table top, said turnstile having a plurality of circumferentially spaced apart laterally extending arms, said turnstile being so correlated to one of said 55 guide surfaces that one of said arms normally extends into said passageway in position to be engaged and rotated by a ball traveling through said passageway, a shaft fixedly connected to said turnstile and extending below the table top, and a switch device, disposed below the table

top and operably connected to the shaft for controlling the make and break of one or more electrical circuits incident to rotation of said turnstile.

5. A target for use with a ball rolling game having a table top tilted slightly to horizontal and over which balls are rollable, said target comprising means adapted to be mounted on the table top and providing a pair of cooperating spaced apart guide surfaces to form a relatively narrow passageway for a ball rolling over said table top, a turnstile adapted to be mounted on said table top for rotating about an upright axis, in a plane spaced above the surface of said table top, said turnstile having a plurality of circumferentially spaced apart laterally extending arms, said turnstile being so correlated to one of said guide surfaces that one of said arms normally extends into said passageway in position to be engaged and rotated by a ball traveling through said passageway, a shaft fixedly connected to said turnstile and extending below the table top, and a switch device mounted below the table top for controlling the make and break of a plurality of separate electrical circuits, incident to rotation of the turnstile, said switch device including a fixed member, a rotatable member carried on said shaft and rotatable with said turnstile as a unit, a plurality of resilient electrical contact fingers carried by the rotatable member and movable therewith, and fixed contacts on said fixed member, engageable by said resilient contact fingers.

6. A bumper for use with a ball rolling game having a table top tilted slightly to horizontal and over which balls are rollable, said bumper device being adapted for mounting on said table top and including a hollow body having an upright, relatively straight guide wall, guide means adapted to be mounted on said table top disposed in cooperating spaced apart relation to said guide wall to form a relatively narrow passageway for a ball rolling over said table top, a turnstile supported within said body for rotation about an upright axis, said turnstile having a plurality of circumferentially spaced apart arms adapted to be projected through an aperture in the guide wall of the body into said passageway in position to be engaged by a ball traveling therethrough for rotating said turnstile, and a switch device adapted to be mounted below the table top and operably connected to said turnstile for controlling the make and break of one or more electrical circuits incident to rotation of the turnstile.

7. A bumper for use with a ball rolling game having a table top tilted slightly to horizontal and over which balls are rollable, said bumper device being adapted for mounting on said table top and including a hollow body having an upright, relatively straight guide wall, guide means adapted to be mounted on said table top disposed in cooperating spaced apart relation to said guide wall to form a relatively narrow passageway for a ball rolling over said table top, a turnstile supported within said body for rotation about an upright axis, said turnstile having a plurality of circumferentially spaced apart arms adapted to be projected through an aperture in the guide wall of the body into said passageway in posi-

tion to be engaged by a ball travelling therethrough for rotating said turnstile, a shaft fixedly connected to said turnstile and extending below the table top, and a switch device adapted to be mounted below the table top for controlling the make and break of a plurality of separate electrical circuits, incident to rotation of the turnstile, said switch device including a fixed member, a rotatable member carried on said shaft and rotatable with said turnstile as a unit, a plurality of resilient electrical contact fingers carried by the rotatable member and movable therewith, and fixed contacts on said fixed member, engageable by said resilient contact fingers.

15. A bumper for use with a ball rolling game having a table top tilted slightly to horizontal and over which balls are rollable, said bumper device being adapted for mounting on said table top and including a hollow body having an upright, relatively straight guide wall, the remaining wall portion of said body being provided with a resilient bumper band to be engaged by a ball, guide means on said table top disposed in cooperating spaced apart relation to said guide wall to form a relatively narrow passageway for a ball rolling over said table top, a turnstile supported within said body for rotation about an upright axis, said turnstile having a plurality of circumferentially spaced apart arms adapted to be projected through an aperture in the guide wall of the body into said passageway in position to be engaged by a ball traveling therethrough for rotating said turnstile, and a switch device adapted to be mounted below the table top and operably connected to said turnstile for controlling the make and break of one or more electrical circuits incident to rotation of the turnstile.

20. A bumper for use with a ball rolling game having a table top tilted slightly to horizontal and over which balls are rollable, said bumper device being adapted for mounting on said table top and including a hollow body having an upright, relatively straight guide wall, said body including a removable top, and the upper portion of the body proper, adjacent the ends of the guide wall, being notched to receive a portion of an annulus of resilient material extending inside the body, and the remaining portion of said annulus being trained around the remaining wall portion of the body in position to be encountered by a ball, guide means adapted to be mounted on said table top disposed in cooperating spaced apart relation to said guide wall to form a relatively narrow passageway for a ball rolling over said table top, a turnstile supported within said body for rotation about an upright axis, said turnstile having a plurality of circumferentially spaced apart arms adapted to be projected through an aperture in the guide wall of the body into said passageway in position to be engaged by a ball traveling therethrough for rotating said turnstile, and a switch device adapted to be mounted below the table top and operably connected to said turnstile for controlling the make and break of one or more electrical circuits incident to rotation of the turnstile.
